CLOCK

Julius Silversteen, North Franklyn, Conn., assignor of one-half to Elsie Mayer, North Franklyn, Conn.

Application August 6, 1942, Serial No. 453,845

2 Claims. (Cl. 194—19)

The present invention relates to clocks and comprehends the provision of a means whereby the insertion of a coin in the clock is a necessary prerequisite to permit winding thereof, the object being to encourage and promote the saving of money.

In carrying out the invention, means is provided to prevent rotation of the winding shaft of the clock mechanism until after a coin has been inserted in the clock, whereupon the winding shaft is released for a predetermined period of time, during which the clock can be wound.

One of the chief characteristics of the invention resides in the simplicity of the means employed for carrying the invention into effect, thereby assuring both positive and accurate operation of said means for the purpose intended.

Other objects and advantages will appear when the following detail description is read in connection with the accompanying drawings, the invention residing in the combination, construction and arrangement of parts as claimed.

In the drawings forming part of this application, like numerals of reference indicate similar parts in the several views, and wherein:

Figure 1 is a rear elevation of a clock partly broken away, and constructed in accordance with one embodiment of the invention.

Figure 2 is a similar view with the rear plate of the clock removed to illustrate certain parts of the invention.

Figure 3 is a similar view showing the means for holding the winding shaft of the clock against rotation.

Figure 4 is a vertical sectional view through the clock.

Figure 5 is a detail sectional view.

Figure 6 is a perspective view of the element employed for retaining the winding shaft holding means normally in active position.

Before entering into a detail description of what is herein shown, I desire to have it understood that the drawings are merely illustrative of one embodiment of the invention, to which I do not limit myself, and that such changes in construction may be resorted to when desired as fall within the scope of what is claimed.

Referring to the drawings in detail, A indicates generally a clock of any well known make or construction, and B the usual mechanism thereof. The lower portion of the clock casing is provided with a money receiving compartment, access to which is controlled in any suitable manner, preferably by a removable plate 11, normally locked in its active position by a suitable lock indicated at 11'. Manifestly, the plate 11 closes an opening in the bottom of the clock casing, while the top wall of the latter is provided with a coin receiving slot 12. This slot is normally covered to prevent dirt or other foreign matter from entering the clock, and this is preferably

accomplished by a flange 13 carried by one wall of a coin receiving chute 14. The chute 14 is mounted within the clock casing for tilting movement as clearly shown in Figure 4, and is actuated by a lever 15 operating through a slot 16 in the rear wall of the clock casing as illustrated. Upon inspection of Figure 4 it will be noted that the chute 14 normally occupies a vertical position slightly to one side of the coin slot 12, with the flange 13 disposed directly beneath the slot 12 and closing the latter. The normal position of the chute 14 is indicated by full lines, and is maintained in this position by a light spring 15'. The tilted position of the chute is shown by dotted lines.

Located directly beneath the coin chute 14 is a stationary channel shaped coin guide, one wall of which is provided with an upstanding angularly shaped flange 17 constituting a stop for the coin chute 14 when the latter is tilted. The coin C passes through the coin chute 14 when the latter is tilted, and momentarily reposes upon the flange 17 until the coin chute 14 returns to its normal position, whereupon the coin C moves therefrom into the stationary coin guide 18 from which it passes into the coin receiving compartment 10 of the clock casing. Arranged within the coin guide 18 is a bowed spring 19 utilized to force the coin from the coin guide through the open side thereof. The coin C enters the coin receiving compartment through a suitable slot 18' beneath which is disposed a freely flexible spring 19'.

Pivoted at one side of the coin chute 14 is a lever of the character illustrated in Figure 6, the purpose of which will be hereinafter fully set forth. This lever is provided with an angularly disposed offset flange 20 normally bridging the coin outlet passage of the stationary coin guide 18 as clearly shown in Figure 2. The lever itself is indicated at 21 and provided with an opening 22 at which point it is pivoted. The flange 20 projects from the lever at an appropriate point in its length to be contacted by the coin C as the latter passes from the coin guide, thereby actuating the lever for a purpose to be presently set forth. A light spring 23 is preferably employed to maintain the lever in its normal position with the flange 20 bridging the outlet passage for the coin in the coin guide 18. The lever 21 is employed to positively maintain the locking means for the winding shaft in its active position, so that the latter cannot be rotated without first depositing a coin in the clock. Consequently, the lever 21 is actuated by the coin C as it is forced from the coin guide 18 under the influence of the spring 19, to effect a release of the winding shaft locking means in a manner to be presently described.

The means for locking the winding shaft against rotation, embodies a lever centrally

mounted on the minute shaft and suitably balanced thereon to operate in the manner and for the purpose to be hereinafter described. Of course, this lever can be of any suitable construction or design capable of functioning to accomplish the desired result, but is preferably of the outline shown. In the specific embodiment of the invention herein illustrated, the lever 24 is characterized with oppositely disposed curved arm-like extensions 25 and 25' respectively. The extension 25 terminates to provide a right angularly disposed extremity 26 arranged in the path of travel of the coin C, to be actuated thereby as the coin passes from the coin guide 18. The other extension 25' is provided with a curved portion 26' to give balance to the lever 24 on the minute shaft. Projecting from the body of the lever 24 is a pawl 27 adapted to engage a ratchet wheel 28 carried on the winding shaft 30, thus normally preventing rotation of the winding shaft in one direction. The usual winding key for the shaft is indicated at 30', while the key for the minute shaft is shown at 31'. The lever 24 is provided with a hub 33 which frictionally engages the flange of the bushing 32 for the minute shaft as clearly shown in Figure 5. The friction between these parts is regulated by adjusting the tension of the coil spring 35 by means of the nuts 35'. These nuts are threaded on the bushing 32, while the spring 35 is interposed between the nuts and the lever 24 as illustrated. In this connection it is to be understood that the lever 24 is adapted to be partially rotated on the minute shaft to its released position when engaged by the coin C, but the friction between the shaft and lever 24 is such that the latter is returned to its normal position by virtue of the rotation of the shaft. The lever is returned to its normal position slowly, requiring approximately five minutes, thereby affording ample time in which to wind the clock. The lever 21 extends across the offset extremity 26 of the lever 24 in contacting engagement therewith, and is primarily utilized to effectively maintain the lever 24 in engagement with the ratchet wheel 28. However, the lever 21 is first engaged by the coin C and moved thereby to an inactive position, just prior to the shifting of lever 24 to its inactive position by the coin contacting the extremity 26 thereof.

In practise, the movable parts are normally arranged as shown in full lines in Figures 2, 3 and 4. In these views it will be noted that the offset flange 20 of the lever 21 bridges the coin outlet passage of the coin chute 18, as does also the offset extremity 26 of the lever 24. The lower end of the lever 21 also extends across the offset extremity 26 of the lever 24 and in contacting engagement therewith. In this position of the parts, the pawl 27 engages the ratchet wheel 28 thereby normally preventing rotation of the winding shaft in one direction. Again, the tiltable coin chute 14 occupies the full line position shown in Figure 4, with the flange 13 thereof arranged to cover the coin slot 12. Now, when it is desired to wind the clock, it is first necessary to tilt the coin chute 14 to uncover the slot 12 and at the same position the chute 14 to receive the coin C inserted in said slot. The coin C reposes upon the flange 17 of the coin chute 18 until the tiltable coin chute returns to normal position. The coin C then passes into the stationary chute 18 and is forced therefrom by the spring 19. As the coin C moves out of the chute 18 it first contacts the offset flange 20 of the lever 21 moving the latter to its inactive position. Continued move-

ment of the coin C brings it into engagement with the offset extremity 26 of the lever 24 thereby shifting the latter to its inactive position. During this operation the lever 24 turns or rotates on the minute shaft 31 independently thereof and carries the pawl 27 away from the ratchet wheel 28. The winding shaft 30 is thus released so the clock can be properly wound. However, the lever 24 is also frictionally mounted on the minute shaft to turn therewith, and the return of the lever 24 to its normal position after each operation, is by virtue of the rotation of the minute shaft. Consequently, the lever 24 returns to its normal position slowly, requiring approximately five minutes, thereby affording ample time in which to wind the clock. The lever 21 obviously moves to its normal position with the lever 24 as it contacts the offset extremity 26 of the latter, and when the pawl 27 again engages the ratchet wheel, the lever 21 functions to effectively hold said parts so associated, so that the winding shaft cannot be used to wind the clock until a proper coin is inserted in the clock. The invention thus provides both a novel and interesting method of saving coins, and encourages thrift.

While it is believed that from the foregoing description the nature and advantages of the invention will be readily apparent, we desire to have it understood that such changes in construction and arrangement of parts may be resorted to when desired as fall within the scope of the appended claims.

What is claimed is:

1. In a clock mechanism, a ratchet wheel carried by the winding shaft, a lever mounted on the minute shaft and having an offset extremity, a pawl projecting from the lever and engaging the ratchet wheel to normally hold the winding shaft against rotation in a winding direction, said lever being partially rotated on its shaft to a released position by a coin contacting said offset extremity thereof, means effectively maintaining said lever in its normal position, including a spring influenced pivoted lever engaging the said offset extremity of the first mentioned lever, an angularly disposed flange projecting from the spring influenced lever and adapted to be engaged by said coin to initially shift the lever to a released position just prior to the movement of the first mentioned lever by said coin, and means whereby the first mentioned lever is returned to its normal position after each operation by the rotation of said minute shaft.
2. A clock having a coin receiving slot in one wall thereof, and a coin receiving compartment, a coin chute pivoted within the clock and arranged at one side of said slot, a flange carried by said chute and normally disposed beneath the slot to close the latter, means for tilting the chute to a position to receive the coin inserted in the slot, and incidentally uncover the slot, means normally holding the winding shaft of the clock against rotation in a winding direction, said holding means including means operable upon movement of the chute to a slot covering position and release of the coin from said chute for effecting release of said winding shaft whereby the latter may be rotated in a winding direction, and means operable by rotation of the minute shaft whereby the said coin actuated means is returned to its normal position after each operation, within a predetermined period of time.
